L. D. CHANDLER

SIGNAL DEVICE FOR FIRE SPRINKLER AND OTHER SYSTEMS

Filed Aug. 25, 1921

UNITED STATES PATENT OFFICE.

LEONARD D. CHANDLER, OF NORTH ABINGTON, MASSACHUSETTS.

SIGNAL DEVICE FOR FIRE SPRINKLER AND OTHER SYSTEMS.

Application filed August 25, 1921. Serial No. 495,390.

The invention to be hereinafter described relates to signal devices for fire sprinkler and other systems, and is an improvement upon the apparatus disclosed in Letters Patent No. 1,215,909, granted to me, February 13, 1917.

The usual sprinkler system comprises a main pipe supplying water to branch pipes having automatic sprinkler valves. A 10 weighted check valve is provided in the main pipe at the entrance to the system, and resists flow of water through the main pipe to the branch pipes of the sprinkler system. The consequence is that there is a tendency 15 to establish a differential water pressure above and beneath the check valve.

It is essential that the signal or alarm shall be given when a sprinkler valve opens, and only at such time. When a valve opens, 20 the water tends to flow into the system, and the pressure drops in the system.

Flow of water into the system toward the sprinkler valves and back out of the system away from said valves, may occur when a 25 valve is not open, and pressure variations may occur when a valve is not open. The following conditions may exist: —

Pressure.

30 *Condition a.*—Pressure tends to rise in the system when the pressure of the supply to the system rises from whatever cause, such, for example, as water hammer or filling of stand pipes;

35 *Condition b.*—Pressure tends to fall in the system when the pressure of the supply to the system falls from whatever cause;

40 *Condition c.*—Pressure tends to fall in the system when the sprinkler valves open or bad leaks occur in the system.

Flow.

45 *Condition d.*—Water tends to flow up into the system when the pressure of the water supply rises from whatever cause;

Condition e.—Water tends to flow back out of the system when the city pressure falls from whatever cause;

50 *Condition f.*—Water tends to flow up into the system when the sprinkler valves open or bad leaks occur in the system.

A signal device depending upon or operating in response to pressures in the system, must distinguish between conditions *b* and *c* 55 to avoid false alarms, since under each of said conditions, the pressure falls, but in

condition *c* the sprinkler valves open, and an alarm is desired, whereas, in condition *b* the sprinkler valves do not open, and an alarm is not desired. Condition *b* may be 60 distinguished from condition *c* by a device responsive to the flow of water in the supply pipes to the system. In condition *b*, water flows down out of the system. In condition *c*, water flows up into the system. 65

A signal device dependent upon or operating in response to the direction of flow of water in the supply pipes for the system, must distinguish between conditions *d* and *f* to avoid false alarms, since in each of said 70 conditions, the flow of water is in the same direction, but in condition *f*, the sprinkler valves open and an alarm is desired, whereas in condition *d*, the sprinkler valves do not open, and an alarm is not desired. Condition *d* may be distinguished from condition *f* by a device responsive to changes in 75 pressures in the system. In condition *f*, the pressure in the system falls. Thus, it is clear how a device responsive to the direction of flow in the supply pipes will distinguish condition *b* from condition *c*, and it is clear how a device responsive to changes of pressures in the system, will distinguish condition *d* from condition *f*. 80

If the flow responsive device and pressure responsive device acting independently of each other, are used jointly to control the operation of a signal, the latter will be given only when conditions *c* and *f* exist, and at 85 no other times.

The aim and purpose of the present invention is to provide a simple, efficient, reliable device which will give a signal only when the sprinkler valves open or bad leaks 90 occur in the system. 95

The character of the invention will be best understood by reference to the following description of one good form thereof shown in the accompanying drawing, wherein : 100

Fig. 1 is a view partly in elevation and partly in section, of a sprinkler system equipped with a signal device embodying the invention;

Fig. 2 is a diagram of a modified form 105 of the invention; and

Fig. 3 on an enlarged scale is a sectional detail to be referred to.

Referring to the drawing, 1 designates a main pipe for supplying water to the branch 110 pipes of the system, a single branch pipe 3 being shown herein provided with sprin-

klar valves 5 which may be of usual construction, and therefore, it is unnecessary to show and describe the same in detail herein.

A check valve 7 is provided in an enlarged chamber 9, and is urged toward its seat by a weight 11. Access to said valve may be had by removal of a hand cover 13.

As stated, the weighted check valve tends to produce a differential pressure in the main pipe above and beneath said valve. Since differential pressure causes flow or tendency to flow, it is proper to speak of a device operated in response to differential pressure in this respect as a flow responsive device.

The flow responsive device, in the present instance, comprises a casing 15 (Fig. 1) having a globular head 17 provided with a window 19. A neck 21 connects the head with a flange 23 opposed to a plate 25, said flange and plate being recessed to provide a chamber 27. A diaphragm 29 of leather or other suitable material, is interposed between the flange 23 and plate 25, said parts being secured together by through bolts 31.

A contact pin 33 is connected to the diaphragm and projects through the neck up into the globular head 17. The diaphragm and contact pin are urged downward by a coil spring 35 encircling the pin and confined between the upper side of the diaphragm and the upper end of the neck. A contact 37, in the present instance, in the form of a reversely bent strip of resilient metal, is secured to the lower end of a pin 39 fitted into an insulation sleeve 41 in a plug 43, said pin being held loosely and positively in a plug 43 by the nuts 45, and a shoulder on the pin at the bottom of the sleeve 41. Upon the pin is provided a nut 46 for connecting a wire to the pin, as will be later described. The plug 43 is threaded into a gland 47, threaded in turn in a stuffing box 49 formed in a cap 51 threaded into the upper end of the globular head. By adjustment of the plug 43 threaded in the gland 47, the contact 37 may be raised or lowered to a position in which it has the proper relation to the contact pin 33.

Pressure variations in the main pipe above the check valve may be transmitted to the upper side of the diaphragm through a pipe, 53, and pressure variations in the main pipe beneath the check valve may be transmitted to the under side of the diaphragm through a pipe 55.

The coil spring 35 normally holds the contact pin 33 out of engagement with the contact 37. If the pressure beneath the check valve rises sufficiently over that above the check valve, the diaphragm will be flexed upward, thereby moving the contact pin 33 into engagement with the contact 37 to close at this point the circuit which will be described. The flow responsive de-

vice just described as constructed to be actuated by the differences in pressure at the opposite sides of the check valve 7, constitutes a good practical construction, but it will be apparent that other types of flow responsive devices or flow meters may be employed and that they may be located at various points in the system other than at the check valve 7 as shown. If desired several flow responsive devices may be employed in the signaling system and associated with the different branch pipes of the system to indicate when the sprinkler valves of a particular branch pipe are opened.

The device responsive to pressure variations in the system above the check valve 7, in the present instance of the invention, comprises a hydropneumatic air tight tank 97 and a casing 57 provided with a diaphragm 59, a contact pin 61 and a contact 63 carried by an adjustable pin 65 provided with nuts 67. Since these parts may be similar to those already described, for the differential pressure or flow responsive device, it is unnecessary to describe the same in detail.

Pressure variations may be transmitted through a pipe 69 from the main pipe above the check valve to the upper side of the diaphragm 59, and from the under side of the diaphragm 59 through the pipe 71 to the lower end of the tank 97.

The pipes 72 and 83 connect to pipes 69 and 71 and by-pass the diaphragm 59. The pipe 72 is provided with a fitting 73 containing a partition 75 having an opening forming a seat for a ball check valve 77 urged toward its seat by a weight 79 in a hood 81. This valve tends to produce a small differential pressure, and allows flow in one direction from tank 97 to main pipe 1.

The pipe 83 is provided with a fitting 85 having a partition 87 therein having a hole forming a seat for a ball check valve 89, urged towards its seat by a weight 91 in a hood 93. This valve tends to produce a small differential pressure and allows a flow in opposite direction from ball check valve 77; that is from main pipe 1 to tank 97. A seepage port 95 is provided in the partition 87, for a purpose to be described.

The differential set up by the small weighted ball check valves is sufficient to cause the diaphragm 59 to operate before water flows through them. This differential should be less than that due to weight in the main check valve 7. The purpose of the small differential ball check valves 77 and 89 and seepage port 95 are to enable the air pressure in the tank to equalize with that in the main pipe 1 or system as quickly as possible, so that it may always be ready to respond to any change of pressure in the system. As pressures in the system change, the water tends to flow back or forth be-

tween the tank and the system. The diaphragm 59 responds to this flow.

These differentially weighted opposed check valves by-passing the diaphragm 59, 5 relieve it of excessive pressure differences and thereby prevent damage to it.

The air-tight tank 97 may be partially filled with water. Suitable means may be provided to indicate the level of the water 10 in the tank. In the present instance, this means comprises a series of small tubes 99 entered through holes in the base of the tank. The upper ends of these tubes are open and at different levels in the tank, and their 15 lower ends are provided with cocks 101. Pin holes 103 in these tubes near the bottom, admit water very slowly into the lower ends of the tubes, and furnish a water seal for the cocks to prevent air leaks. When it is de- 20 sired to determine the level of water in the tank, these cocks can be opened, and if air blows from the pipes, it will indicate that the water level is beneath the upper ends thereof. If water flows from the pipes, it 25 will indicate that the water level is above the upper ends thereof.

The pipe 71 may be provided with a valve 105 through which more air may be pumped into the tank if desired. A strainer 107 of 30 usual construction, may be interposed in the pipe 69 adjacent its juncture with the main pipe, to prevent solids from passing through the pipes 69 and 71, and to the devices in communication therewith.

35 The construction is such that when water enters the system, its flow is through the pipe 72, through the seepage port 95 and the fitting 85, and through the pipes 83 and 71 to the tank, and if the pressure is great 40 enough to lift the ball valve 89 from its seat, the flow will be transmitted past said valve to the tank. The pressure in the system is always maintained in the tank. The cushion or air compressed in the tank above 45 the level of the water therein, serves as a source of energy to press the diaphragm 59 upward and urge the contact pin 61 into engagement with the contact 63 to complete the circuit at this point. It will be under- 50 stood that this source of energy does not become active to close the circuit at this point, unless the pressure in the system falls. If the pressure in the system rises, the pres- 55 sure will be transmitted through the pipe 69 to the upper side of the diaphragm 59, the contact pin will be moved or held down out of engagement with the contact 63, and the air in the tank will be compressed.

When the sprinkler valves open, or serious 60 leakage occurs in the system, the signal should be given. Any suitable form of signal may be employed, and in the present instance, the signal is in the form of an electric bell 109 of usual construction.

65 A battery 111 or other source of electricity

may have one end of a wire 113 connected to a positive pole of the battery, and its opposite end connected by the nuts 46 with the contact pin 39. A wire 115 has one end connected by nuts 67 to the contact pin 65 70 referred to, and its opposite end connected to an insulated terminal 117 on a base plate 119. An electro-magnet 121 is mounted on this base plate, and one end of the coil 123 of the magnet is connected to the insulated 75 terminal 117, and the opposite end of said coil is connected to an insulated terminal 125 on the base plate. A wire 127 leads from the insulated terminal 125 to branch wire 129 and 131, the former being connected to a negative terminal of the battery, and the latter being connected to the electric bell. A wire 133 has one end connected to the electric bell, and its opposite end connected to an insulated terminal 135 on the 80 base plate. A wire 137 has one end connected to the wire 113 referred to, and its opposite end connected to a terminal 139 which is grounded on the base plate.

Co-operating with the magnet is an armature 141 fulcrumed on a lug 143 on the base plate and serving as a trigger for a knife switch 145 pivoted on the base plate and urged by a coil spring 145 toward an insulated contact 147 connected to the terminal 95 135. This switch may have a reset handle 149.

In operation, when the sprinkler valves open, water flows into the system, and is accompanied by a drop in pressure in the 100 system. The flow into the system is caused by a greater pressure beneath the check valve 7 than above it, and this differential pressure is transmitted by the pipes 53 and 55 to opposite sides of the diaphragm 29. 105 Since the pressure beneath the diaphragm is greater than that above it, the contact pin 33 is moved upward against the resistance of the coil spring 35, and brought into engagement with the yielding contact 37, 110 thereby closing the circuit for the magnet coil at this point.

The drop in pressure enables the energy of the compressed air in the tank 97 to become effective to flex the diaphragm 59 upward, thereby causing the contact pin 61 to move upward against the resistance of its coil spring, and connect with the yielding contact 63, thereby closing the magnet coil circuit at this point.

115 The current passes from the positive pole of the battery through the wire 113 to the contact pin 39, and thence to the contact pin 33. The current passes on through the pipes 53 and 55 to the main pipe 1, and 120 thence through the pipe leading to the casting 57. The current passes through the contact pin 61 and contact pin 65 through the wire 115 to the insulated terminal 117, and thence through the coil 123 of the mag- 125 130

net to the insulated terminal 125. The current passes thence through the wires 127 and 129 to the negative pole of the battery. This completes the circuit to the magnet and energizes the same. As a consequence, the armature 141 is drawn toward the magnet and is tripped from the knife switch 145, thereby allowing the coil spring 145^a to rock the knife switch into engagement with the contact 147. This short-circuits the current to the magnet, and the current now passes from the positive pole of the battery through the wires 113 and 137 to the terminal 139 grounded on the plate 119, thence through the plate to the contact 147 and switch 145 which is also grounded on the plate 119. The current passes thence through the terminal 135 and wire 133 to the bell, and back through the wires 131 and 129 to the negative pole of the battery.

Thus, the circuit is completed to the bell independently of the first circuit including the contacts 37 and 63 which are respectively controlled by flow and pressure. The consequence is that the bell continues to ring until the short-circuit therein is interrupted. This is accomplished by manual adjustment of the knife switch 145 through the reset handle 149.

The contact pins 39 and 65 as stated, are insulated respectively from the casings 15 and 57. To further contribute to the efficient insulation effect, and to keep the contacts in the casings in good condition, said casings may be filled with oil, which as is well known, is a non-conductor of electricity. The oil being lighter than water will always remain above any water which may enter the globular casings past the lower contact pins.

Referring now to the modification shown in Fig. 2, the construction may be similar to that already described, with the exception that it is designed to operate on a normally closed circuit, which makes it necessary to change the construction of the switches which close in response to flow of water into the system accompanied by a drop in pressure, which as stated, are the conditions when the sprinkler valves are open.

The casings 151 and 153 may be similar to the casings 15 and 57 referred to, and the devices contained therein may be similar to the devices contained in the casings 15 and 57, with the exception of the switch construction, which is shown in detail in Fig. 3. The upper contact pin 155 has a spring arm 157 secured thereto, having an end portion 159 tending constantly to remain in engagement with the upper end of the contact pin 161. The upper contact pin 155 also carries a stop 163.

The construction is such that when the lower contact pin 161 is moved upward, the end portion 159 will follow therewith and

remain in engagement with the outer end of the lower contact pin until arrested by the stop 163. Then continued travel of the lower contact pin will cause its head to pass on out of engagement with the arm portion 159, and the latter will be protected from electrical contact with the pin 161 by an insulation sleeve 165 embracing the same.

In this modification the battery 167 has its positive pole connected by a wire 169 with the piping 171 for the pressure responsive device. The current passes thence through the main pipe 1 to the piping 173 for the flow or differential pressure responsive device. The two responsive devices are connected in multiple by wires 175 and 177 to a wire 179 connected to the coil 181 of the magnet 183. A wire 185 leads from this coil back to the negative pole of the battery.

The positive pole of the battery is connected by a wire 187 with the electrical bell 188, and a wire 189 leads from the electric bell to a fixed contact 191. An adjacent fixed contact 193 is connected by a wire 195 with the negative pole of the battery.

Co-operating with the magnet is an armature 197 on a pivoted arm 199 carrying a switch 201 for co-operation with the fixed contacts 191 and 193.

The construction is such that when the sprinkler valves open and water flows into the system accompanied by a drop in pressure, the flow responsive switch 203 will be opened, and the pressure responsive switch 205 will be opened, thereby breaking the circuit to the magnet coil at two points. This will de-energize the magnet and allow the armature 197 to drop and swing the lever 199 so as to cause the switch 201 to connect the contacts 191 and 193, thereby closing the circuit to the electric bell. The bell will continue to ring until its circuit is broken by movement of the switch 201 out from engagement with the fixed contacts 191 and 193.

It will be understood that in either modification, the flow responsive switch and the pressure responsive switch act wholly independently of each other, and that their concurrent operation to produce the operation of the signal only occurs when the sprinkler valves open, and when said valves open, two conditions exist which do not concurrently occur at any other time, that is, the condition of a flow of water into the system, and the condition of a fall of pressure in the system.

When the pressure of the supply to the system rises from any cause, such, for example, as water hammer or filling of stand pipes, this pressure will act on the upper side of the diaphragm 59, and hold the switch 63 open and prevent giving the signal.

If the pressure falls in the system when

the pressure of supply to the system falls from whatever cause, the pressure above the diaphragm 29 is greater than beneath it, and the switch 37 is held open and prevents 5 giving the signal.

If water flows up into the system when pressure of the supply rises from whatever cause, the pressure above the diaphragm 59 is greater than the pressure beneath it, and 10 the switch 63 is held open and prevents giving the signal.

If water flows back out of the system when the city pressure falls from whatever cause, the pressure above the diaphragm 29 is 15 greater than the pressure beneath it, thereby holding the switch 37 open and prevents giving the signal.

If, however, the sprinkler valve opens or 20 bad leaks occur in the system, water flows up into the system and the pressure falls in the system. The differential pressure on the diaphragm 29 caused by this condition and the weighted check valve 7, closes the switch 37, and this fall in the static pressure in the 25 system, allows the air cushion in the tank 97 to become effective to move the diaphragm 59 upward and close the switch 63. Closing the circuit at these two points, completes the circuit to the electro-magnet, which operates 30 the switch which completes the circuit to the electric bell. The closing of the two 35 switches, therefore, serves to initiate the signal, but the signal after once initiated, continues after the closing of said switches, and opening of either or both of said 40 switches will not interrupt the signal, which will continue until manually interrupted.

The apparatus is simple and cheap in construction and reliable in operation.

40 It will be understood that the invention is not limited to the specific embodiments shown, and that various deviations may be made therefrom without departing from the spirit and scope of the appended claims.

45 What is claimed is:

1. In combination with a fire sprinkler system having automatic sprinklers, a signal, controlling means for said signal including an electric circuit, a casing provided 50 with a diaphragm, a switch included in said circuit and actuated by said diaphragm, means for subjecting one side of the diaphragm to the static pressure of the water in said system, an air-tight container 55 containing air for exerting pressure upon the opposite side of said diaphragm and adapted to actuate the switch upon a drop in pressure in said system, a connection between said container and system for correcting pronounced differences in pressure between 60 the container and system, and a yielding resistance in said connection for resisting the free transmission of pressure through the connection.

65 2. In combination with a fire sprinkler

system having automatic sprinklers, a signal, an electric switch, an electric circuit connecting the signal and switch, an air-tight container connected to the sprinkler system and containing a gaseous fluid forming a cushion that is subjected to the pressure of the water in said system, a differential pressure responsive device for controlling said switch and connected between the container and said system to be actuated by 70 a drop in the pressure of the water in the system below the pressure in said container, and means for promptly correcting pronounced differences in pressure between said container and system but adapted to maintain an appreciable difference in pressure 75 therebetween.

3. In combination with a fire sprinkler system having automatic sprinklers, a signal, an electric switch, an electric circuit 80 connecting the signal and switch, an air-tight container connected to the sprinkler system and containing a gaseous fluid forming a cushion that is subjected to the pressure of the water in said system, a pressure responsive device for controlling said switch and connected to said container to be actuated by a drop in the pressure of the water in the system below the pressure in said container to actuate said switch, and means for 85 correcting pronounced differences in pressure between said container and system but adapted to maintain an appreciable difference in pressure 90 therebetween.

4. In combination with a fire sprinkler 100 system having automatic sprinklers, a signal, an electric switch, an electric circuit connecting the signal and switch, a diaphragm for controlling the switch, means for subjecting one side of the diaphragm to the pressure within said system, a fluid cushion device for exerting pressure upon the other side of the diaphragm to actuate the switch when a drop in the pressure of the system occurs, means for automatically 105 varying the pressure of the fluid cushion in response to variations of pressure in said system to thereby relieve the diaphragm from excessive strains and including flow opposing means for producing an appreciable difference in pressure between the cushion device and system.

5. In combination with a fire sprinkler system having automatic sprinklers, a signal, an electric switch, an electric circuit 110 connecting the signal and switch, a differential pressure responsive device for controlling the switch, means for subjecting one side of the pressure responsive device to the static pressure within said system, a cushion 115 device containing gaseous fluid for exerting pressure upon the other side of the pressure responsive device, means for automatically varying the pressure of the cushion device in response to the variations of pressure in 120 125 130

said system to thereby relieve the pressure device from excessive actuating pressure and including flow opposing means for producing an appreciable difference in pressure between the cushion device and system.

6. In combination with a fire sprinkler system having automatic sprinklers, a signal, an electric switch, an electric circuit connecting the signal and switch, a differential pressure responsive device for controlling the switch, means for subjecting one side of the pressure responsive device to the static pressure within said system, a fluid cushion device for exerting pressure upon the other side of the pressure responsive device to actuate the switch, means for automatically varying the pressure of the cushion device in response to variations of pressure in said system to thereby relieve the device from excessive actuating pressure, and a check valve between the fluid cushion device and system for yieldingly resisting the transmission of pressure from one to the other.

25 7. In combination with a fire sprinkler system having automatic sprinklers, a signal, controlling means for the signal including an air-tight tank, a diaphragm responsive to pressure differences between the system and air pressure in said tank, means controlled by the diaphragm for actuating the signal, a pipe connection between said tank and system for relieving excessive differences in pressure between them, and means for opposing to a slight degree the flow of 30 fluid between the tank and system.

40 8. In combination with a fire sprinkler system having automatic sprinklers, a signal, controlling means for the signal including a fluid tight casing having electric contacts supported in the casing, an electric circuit between said signal and contacts, a diaphragm mounted in said casing and connected to one of the contacts to move it into and out of engagement with the other contact, an air cushion device, connections for subjecting one side of the diaphragm to the pressure in said system and the opposite side to the pressure of the air cushion device, means for automatically varying the pressure of the fluid cushion in response to variations of pressure in said system and including flow opposing means for producing an appreciable difference in pressure between the air cushion device and system.

9. In combination with a fire sprinkler system having automatic sprinklers, a signal, controlling means for the signal including a fluid tight casing having a diaphragm mounted therein and contacts mounted in the casing above the diaphragm, an electric

circuit between the contacts and signal, means connecting one of the contacts to the diaphragm to be actuated thereby to open and close the circuit, an air cushion device, 65 connections for subjecting one side of the diaphragm to the pressure in said system and the other side to the pressure of the air cushion, means for automatically varying the pressure of the fluid cushion in response to variations of pressure in said system and including means for maintaining a slight difference in pressure between the fluid cushion and system. 70

10. In combination with a fire sprinkler system having automatic sprinklers, a signal controlling means for the signal including a differential pressure responsive device connected to said system, a device including a fluid cushion operable in response to static pressure variations, a connection between the fluid cushion and the differential responsive device and also between the fluid cushion and sprinkler system for correcting pronounced differences in pressure between the cushion and system, means associated with said connection for maintaining an appreciable difference in pressure between the fluid cushion and system, and means controlled by said devices for actuating the signal. 75 80 85 90

11. In combination with a fire sprinkler system having automatic sprinklers, a signal, controlling means for the signal including differential pressure responsive means for actuating the signal, an air cushion device, two weighted check valves in independent by-passes leading from the system to the air cushion device and one being adapted to check the flow in one direction and the other in the opposite direction and operable to correct pronounced differences in pressure between the system and air cushion, and means connecting one side of the differential pressure responsive means to the air cushion and the other side to said system. 95 100 105

12. In combination with a fire sprinkler system having automatic sprinklers, a signal, an air cushion device, a connection between the air cushion device and system for correcting pronounced differences in pressure therebetween, comprising weighted check valves arranged to by-pass the water flowing in either direction between the cushion device and system, a diaphragm for actuating the signal, and means for subjecting one side of the diaphragm to the pressure in the system and the opposite side to the pressure in said cushion device. 110 115

In testimony whereof, I have signed my name to this specification. 120

LEONARD D. CHANDLER.
